VALVE CONSTRUCTION FOR
REGENERATIVE FURNACES

Haakon Hellan, Cleveland Heights, Ohio

Application December 8, 1947, Serial No. 790,314

5 Claims. (Cl. 263—15)

1

This invention relates to regenerative furnaces such as open hearth furnaces for production of steel, and more specifically relates to valves used for controlling the flow of air and waste gas through the regenerative heat transfer units to and from the open hearth furnace.

As is well known, an open hearth furnace usually has associated with it two or more different regenerative chambers operatively connected to the open hearth furnace so that air can be forced through one of such regenerative chambers and then to the open hearth furnace after which the waste gases flow through the second regenerative chamber and out to the atmosphere through a chimney. The operation is such that one regenerative chamber is heating the input air while the second regenerative chamber is absorbing heat from the waste gases passing therethrough. The flow through the regenerative chambers is periodically reversed so that the heat stored in one chamber can be used for preheating the input air, accordingly, easily operated valves must be provided to control the flow of air and gas therethrough. These regenerative chambers are heated to high temperatures by the large volume of gases passing therethrough so that the valve means not only must be of appreciable size but must be adapted to withstand high temperatures, as well as wide fluctuations in temperature.

The valve means usually include an air valve at floor level for admitting air to a regenerative chamber, and a flue damper to control the flow of waste gas from the regenerative chamber to the chimney flue and stack. One commonly used construction at present has the flue damper connected to a saucer valve with a limited vertical movement for opening and closing in relation to its seat. The flue damper connects to the saucer valve by a flexible rope on opposite sides of a sheave. The rope slackens when the saucer valve closes on its seat and the weight of the air valve ceases to pull on the flue damper which always is suspended through suitable sheave means from an operating mechanism. Usually there are two sets of air valves and flue dampers provided for each open hearth furnace with one set being associated with each regenerative chamber. Hence the mechanism used to operate the sets of air valves and the flue dampers must be adapted to function under variable load conditions and to take up slack in the flexible rope connecting the air valve and flue damper after the air valve seats on the valve seat provided therefor.

2

Another problem relating to valves for open hearth regenerators is that the hood provided over the damper is usually designed for being positioned at the arch level. Furthermore, all modern furnaces have deep flues in their regenerative systems so that deep pits must be provided in the floor for access to the cooling pipes used for the valves.

The present invention is particularly concerned with the type of flue damper that has a seat with a single horizontal opening therein for registering with a flue having an independent vertical air inlet, as distinguished from the double decked type of damper construction wherein the air inlet is through a second horizontal port immediately above the flue, and where the one damper will close both to stack or air alternatingly. A very serious problem in present valve construction is caused by the change in practise from using natural air sucked in at the air valves to the use of forced air of considerable pressure as furnished by a fan, and introduced at the same air valves, which then are enclosed in casings. The flue damper slides on the seat with the face toward the stack flue. The injection of forced air behind the damper will cause it to sway from the seat, leak cold air into the stack and kill the draft. The situation in the double decked construction is similar at the upper port, where the small weight component of the damper is far insufficient to balance the air pressure behind it.

The general object of the present invention is to avoid and overcome the foregoing and other difficulties with the present type of valve constructions for regenerative furnaces and to provide a valve assembly with a positive correlation between the action of the air valve and flue damper and a positive closing force against the seat of both damper and air valve.

Another object of the invention is to provide an air gate valve which is attached to a flue damper by a flexible connecting means with the air valve and flue damper being in continued opposed suspension.

Another object of the invention is to design the damper and air valve so that the air valve can operate on exactly one-half the movement of the damper to simplify the connection of the means correlating their movement.

A further object of the invention is to extend the seat for the damper up to the floor level and to associate the same fixedly with the hood providing for the air transmittal means.

Yet another object of the invention is to pro-

vide a hood for covering an opening in the flue arch and to utilize this opening as a vertical passageway for transmitting air to the flue.

Another object of the invention is to use separate, vertically movable gate valves for controlling the air flow to each regenerative chamber of a furnace.

A still further object of the invention is to provide a damper, the cooling pipes for which serving as the valve stem of the damper.

Yet another object is to provide a forced draft system for a regenerative furnace with a common blower for a plurality of regenerative chambers and with straight connecting ducts for the fast flowing air.

Another object of the invention is to provide flue dampers with novel dry web construction for withstanding severe temperature changes so as to avoid warping and to benefit from air cooling by the inflowing air.

These and other objects of the present invention will become more apparent and better understood from the following detailed description taken in conjunction with the accompanying drawings; wherein

Figure 1 is a plan view of a portion of a regenerative unit and of valve means therefor embodying the principles of the present invention;

Figure 2 is a vertical section view taken on line 2-2 of Figure 1 with additional control means therefor shown in diagrammatic form;

Figure 3 is a front elevation of the damper and cooling pipes therefor of the invention; and

Figure 4 is a vertical section taken on line 4-4 of Figure 3.

Reference now is made to the details of the construction shown in the accompanying drawings wherein numerals 1 and 2 designate regenerator flues which lead from the furnace regenerators (not shown) and into a common flue 3 that extends to a waste heat boiler or chimney. The flues 1 and 2 are usually provided with arched top portions. In order to force air into the regenerators when desired, a conventional blower or fan indicated by the number 4 is provided on the floor above the flue 3. The blower 4 is driven by a conventional motor 4a and forces air into a junction tank 5 which has air outlet ducts 9 and 10 connected thereto. The junction tank 5 is shown as provided with a removable top 6 which may be readily opened to permit the flow of air into the intake ducts in the event of failure of the fan 4 or motor 4a.

Each air duct 9 and 10 is provided for connection to one of the furnace regenerators and connects thereto through corresponding means, one example of which is best shown in Figure 2. The air ducts 9 and 10 connect to hoods 11 and 12 that are positioned over vertically extending passages 16 that connect the hoods individually to the flues 1 and 2 with which they are associated.

Air flow through the air ducts 9 and 10 is controlled by means of gate valves 7 and 8. The valves 7 and 8 each include a ribbed cast iron gate 13 which is slidably associated with a cast iron valve seat 14 which is fastened by any suitable means to a casing section 15 that is associated with the air duct and is positioned outwardly of same in association with the air valves. The gates 13 are positioned for movement in a vertical plane so that they can be moved from positions without the ducts to positions within the ducts for controlling or preventing air flow through the same. The casing

sections 15 have upwardly extending extensions 15a for receipt of the gates 13 in their open positions.

Flow of waste gases from flues 1 and 2 into the common flue 3 is controlled by means of dampers, such as a damper 17 that is slidably mounted against a seat within the flue 1. This damper 17 is provided with a water cooled rim substantially as is shown in my prior Patent 2,048,696. The lower portion of the damper web 18 consists of a separate, replaceable alloy metal plate 18 which is secured to the damper 17 by bolts 18a extending through enlarged bolt holes in the plate. Thus, the independent damper plate can contract and expand appreciably in relation to the damper frame, with a minimum of warping or buckling of the same since the temperature of the damper plate varies widely. The damper 17 is slidably positioned on a cast iron seat 19 provided therefore, which seat is water cooled in a similar manner to the damper by means of cooling coil 20a. Water or other cooling means is carried to the seat 19 by means of a pipe 20 which extends through the hood 11 and is exhausted therefrom by a pipe (not shown) that usually extends along the opposite wall of the passage 16.

Figure 3 best shows that a cooling coil 36 is provided in the damper 17. This damper 17 may have a plurality of ribs 17a provided on its upper outer surface for contact with air flowing into the regenerator unit. These ribs 17a are usually cast integral with the remainder of the damper. Similar ribs may be provided on the alloy plate 18.

So as to maintain the damper 17 at reduced temperatures, two pipes 21 connected to the coil 36 extend therefrom and pass through holes in a cover section 22 removably associated with the hood 11. The pipes 21 have a plate 23 secured thereto adjacent their upper ends, which plate is used in suspending the damper and in controlling the position of the same. Guide means, such as substantially vertically extending guide bars 19a, are associated with the cast iron damper seat 19 and extend therefrom in the plane thereof up to a point adjacent the floor level of the apparatus. These guide devices 19a provide means on which the damper 17 can be slid so as to open the flues 1 and 2 to flue 3.

Movement of the damper 17 is controlled through means of a conventional motor 28 which has a drum 27 associated therewith to receive a flexible rope 25 which in turn connects to an eye-bolt 24 secured to the plate 23. The flexible rope 25 passes over a sheave 26 and connects to a counterweight 29, which counterweight is adapted to balance, substantially, the damper 17 less the support provided therefor by the gate 13, as hereinafter explained in detail. The plate 23 also carries an eye-bolt 30 that connects to a second conventional flexible rope 31. This rope 31 extends over a support sheave 32 and secures to an adjustable eye-bolt 34. A sheave 33 is supported by the rope 31 intermediate the support sheave 32 and anchor member 34 and engages with and suspends the air valve 13 by a rod 35 which is slidably received in the casing extension 15a. The gate 13 is completely supported by this rope 31. The apparatus is so designed and arranged that the gate valve 13 must travel one-half the vertical distance that the damper 17 does so as to move from a completely open to a completely closed position. By suspending the gate valve 13 in the manner

shown, it is balancing at least a portion of the weight of the damper 17 at all times and the positions of the gate valve and the damper are made interdependent so that one can only be closed when the other is open and vice versa. Of course, the damper and gate valve must move simultaneously, which is another requisite in controlling air flow through a regenerator unit.

Flexible hose 38 is shown attached to the ends of the pipes 21 for transmittal of cooling fluid to and from such pipes for transmittal to the damper 17. The plate 23 supports the damper 17 as previously indicated, through the pipes 21, and eliminates the use of a central rod, which has heretofore been used in corresponding damper constructions.

From the foregoing, it will be seen that a novel type of damper is provided that is especially suited for wide fluctuations in the temperature to which it is subjected. Likewise, a positive relationship between the damper and air valve is provided, and the two valves are suspended in constant opposition whereby the weight of the air valve will assist in balancing the damper and there will be an effective interlock therebetween to maintain the two devices in proper operative correlation.

Having thus described my invention so that persons skilled in the art may understand and practice the same, what I desire to obtain by Letters Patent is embodied in the appended claims.

I claim:

1. An open hearth reversing system comprising regenerator flues converging into a stack flue, flue dampers for closing said regenerator flues, a blower for furnishing air under pressure to the regenerator flues, horizontally disposed ducts leading from said blower to the said regenerator flues, a vertically movable and constantly suspended gate valve for closing each air duct, flexible means uniting said flue dampers to said air valves, means for correlating the movement of said flue damper with the movement of said air valve, said air valve having approximately half of its weight constantly acting in opposition to said flue damper, a counter weight connected to said flue damper for balancing the remaining weight thereof, and mechanical means for raising and lowering said flue damper and thereby closing or opening said air valve depending upon the position of said flue damper.

2. An open hearth reversing system for regenerator flues which converge to a stack flue, a vertical air passage into each of said regenerator flues, a flue damper seat provided in each of said vertical air passages adjacent the junction of said regenerator flues, a flue damper positioned on said damper seat, a blower for supplying air under pressure to the regenerator flues, an air duct connecting said blower with said vertical air passage above the regenerator flues, a vertically movable gate valve in said air duct for controlling the flow of air to said vertical air passage, and means operatively connecting said vertically movable gate valve to said damper for permitting air flow through said air duct only when said damper is closed.

3. A valve system for a regenerative furnace having flues extending therefrom and joining into a common discharge flue, said apparatus comprising an air duct connecting to each of the flues extending from the regenerative furnace, blower means for forcing air through said air ducts, said air ducts being joined together adjacent to said

blower means, a gate valve for each air duct freely movable in vertical planes from an open to closed position, a damper seat provided in each flue, a damper associated with each of said damper seats and being adapted for movement in a substantially vertical plane for movement from a closed to an open position, a flexible rope connected to each of said dampers and to an elevated support member, the associated gate valve being completely suspended from a sheave in a loop of said flexible rope between said support member and a sheave above the damper, whereby the operation of said air valve is dependent upon the position of said damper, the one actuating and moving in opposition to the other said gate valve being arranged to seat under air pressure from said blower.

4. A valve system for a regenerative furnace including two regenerator flues extending therefrom and connecting to a common collecting flue, said apparatus comprising an air duct leading from each of the flues, blower means for forcing air through said air ducts, said air ducts being joined together adjacent said blower means, a air valve with vertical seat for each air duct, said air valves being movable in vertical planes from open to closed positions and adapted to seat under air pressure from said blower, a damper seat provided in each regenerator flue and positioned adjacent the connection thereto of said air duct but intermediate same and said collecting flue, a damper associated with said damper seat and adapted in a substantially vertical plane for movement to and from an open position, a flexible rope connected to said damper for operating said air valve, fixed means for supporting the other end of said rope, a support sheave engaged with said flexible rope intermediate said fixed means and said damper for supporting said air valve and damper in opposition, a second flexible rope attached to said damper, a drum receiving said second rope, and means for controlling the position of said drum for controlling the vertical positions of said damper, and said air valve being adapted to move from open to closed position with one-half the vertical movement of said damper.

5. A valve system for a regenerative furnace having flues extending therefrom and connecting with a common collecting flue, said apparatus comprising an air duct leading from each of the flues, blower means for forcing air through said air ducts, said air ducts being joined together adjacent said blower means, an air valve with vertical seat for each air duct, said air valves being movable in vertical planes from open to closed position and adapted to seat under air pressure from said blower, a damper seat provided in each regenerator flue and positioned adjacent the connection thereto of said air duct, a damper associated with said damper seat for movement in a substantially vertical plane for movement to and from a flue closing position, a flexible rope connected to said damper for operating said air valve, means for fixedly supporting the other end of said flexible rope, a support sheave engaged with said flexible rope intermediate said supporting means and said damper, said air valve and damper being coupled by said flexible rope so that the weights thereof are in opposition and the positions of same are correlated and one of such members is closed when the other such member is open, a second flexible rope attached to said damper at one end and a counter weight at the other end to balance the pull from the

said damper, a rope drum positioned intermediate said damper and said counterweight, and means for rotating said drum.
